UNITED STATES PATENT OFFICE.

CHARLES LOAR TAYLOR, OF PITTSBURGH, PENNSYLVANIA.

DESIGN FOR A STORE-FRONT.

51,399.

Specification for Design.

Patented Oct. 16, 1917.

Application filed December 4, 1916. Serial No. 135,095. Term of patent 14 years.

To all whom it may concern:

Be it known that I, CHARLES LOAR TAYLOR, a citizen of the United States, and a resident of Pittsburgh, in the county of Allegheny and State of Pennsylvania, have invented a certain new, original, and ornamental Design for Store-Fronts, of which the following is a specification, reference being had to the accompanying drawing, forming part thereof, in which—

Fig. 2 is a cross section of the same, taken on the line 2—2 Fig. 1, and looking in the direction of the arrows.

I claim:—

The ornamental design for a store front, as shown.

In testimony whereof, I, the said CHARLES LOAR TAYLOR, have hereunto set my hand.

CHARLES LOAR TAYLOR.
